CLAIM

The ornamental design for ultrasonic pest repeller, as shown and described.

DESCRIPTION

1. Ultrasonic pest repeller

1.1 : Perspective

1.2 : Front

1.3 : Back

1.4 : Left

1.5:Right

1.6:Top

1.7 : Bottom

1.8 : Perspective

Reproduction 1.1 is a front perspective view of an ultrasonic pest repeller showing our new design; Reproduction 1.2 is a front elevation view thereof; Reproduction 1.3 is a rear elevation view thereof; Reproduction 1.4 is a left side elevation view thereof; Reproduction 1.5 is a right side elevation view thereof; Reproduction 1.6 is a top plan view thereof; Reproduction 1.7 is a bottom plan view thereof;

(Continued)

Reproduction 1.8 is a rear perspective view thereof; This article is used for repelling pest by generating ultrasonic wave itself.
